UNITED STATES PATENT OFFICE.

MARJORIE T. GREGG, OF BROOKLINE, MASSACHUSETTS.

TOY.

1,141,459.

Specification of Letters Patent. Patented June 1, 1915.

Application filed October 15, 1914. Serial No. 866,872.

To all whom it may concern:

Be it known that I, MARJORIE T. GREGG, a citizen of the United States, and resident of Brookline, in the county of Norfolk and 5 State of Massachusetts, have invented new and useful Improvements in Toys, of which the following is a specification.

This invention relates to toys such as dolls, and its object is to provide a durable 10 toy of simple construction which may be readily and economically manufactured and which is peculiarly adapted for use as an equestrian doll.

Referring to the drawings which illustrate an embodiment of my invention,—Figure 1 is a front view of a frame or skeleton of a doll; Fig. 2 is a front view, Fig. 3 is a side view, and Fig. 4 is a front view of the doll body in successive stages of its construction; and Fig. 5 is a front view of the completed doll body.

The frame or skeleton is of wire or similar material and comprises a body portion A, neck portion A', arms A², A³, and legs 25 A⁴, A⁵. Suitable means such as the loops a are provided for securing to the frame an appropriate head, hands and feet.

In making the doll, strips B of suitable material such for example as strips of cotton cloth, called herein arm strips, are wound about the arms and body in the manner shown in Fig. 2. As shown in said figure a strip B is wound around the arm A³ of the frame beginning at a point just above 35 the loop a on said arm and extending up to the shoulder of the frame, then down around the body portion A, the free end of said strip B extending along the leg A⁴. A similar strip B is then wound around the arm 40 A² of the frame to the shoulder, then around the body portion A, the free end of the strip extending along the leg A⁵.

Strips C similar to the strips B and called herein body and leg strips, are then folded 45 over the frame in the manner shown in Figs. 3 and 4. As shown in said figures, a strip C of sufficient length to reach from a shoulder to the foot of the opposite leg both front and back, is laid or folded over a shoulder 50 of the frame, as for instance, the right shoulder, across the body portion A and down along the left leg. Another strip C is then laid or folded over the left shoulder across 55 the body portion A and down along the right leg and so on alternately until the body is of the desired thickness. The strips C

are then firmly secured in any suitable manner as by a strip of fabric or tape D wound around them and fastened, as clearly shown in Fig. 5. It will be understood that when 60 the body of the doll has been completed in the form shown in Fig. 5 a suitable head, hands and feet are secured to the loops a or their equivalents, and the body is provided with appropriate clothing.

It will, I believe, be clear that a doll or other toy made according to my invention as above described is very durable and well calculated to withstand the rough handling to which such articles are subjected. The legs 70 and arms can not be readily torn off as in the case of sewed and rubber dolls and the body is not stuffed according to the common practice of making toys of this character. It will be equally clear that the toy may be 75 very cheaply made; its material being inexpensive and the method of making so simple that it can readily be carried out by comparatively inexperienced persons. Furthermore, by reason of the crossing of the leg 80 and body strips C, as above described, the legs when stretched apart tend to return to normal position so that without bending the wire frame of the legs and so injuring the toy, a doll of this construction sits firmly 85 astride a toy horse or the like.

While I have herein shown and described my invention as embodied in a doll, it will be understood that the invention is applicable to the making of other articles such 90 as toy animals of all sorts. Therefore, the words "arms" and "legs" as herein used are to be understood merely in a descriptive sense and in no wise a limitation of the invention.

I claim:

1. A toy of the character described comprising a skeleton or frame having a body part, arms, and legs, a strip of fabric wound upon one of said arms beginning at its end 100 and extending to the shoulder, thence around the body part and extending along one of said legs, and another strip of fabric wound upon the other of said arms beginning at its end and extending to the shoulder, thence 105 around the body part and extending along the other of said legs, and means to bind said strips about said legs.

2. A toy of the character described comprising a skeleton or frame having a body 110 part, arms and legs, a strip of fabric folded over one shoulder of said frame and extend-

ing along the leg opposite said shoulder, another strip of fabric folded over the other shoulder of said frame and extending along the leg opposite said shoulder, said strips 5 crossing each other, and means to bind said strips about said body part and legs.

3. A toy of the character described comprising a skeleton or frame having a body part, arms and legs, strips of fabric wound upon each of said arms, a strip of fabric folded over one shoulder of said frame and extending along the leg opposite said shoulder, another strip of fabric folded over the other shoulder of said frame and extending 10 along the leg opposite said shoulder, said two last named strips crossing one another, and means to bind said two last named strips about said legs and said body part.

4. A toy of the character described comprising a skeleton or frame having a body part, arms and legs, a strip of fabric wound upon one of said arms beginning at its end 15

and extending to the shoulder, thence around the body part and extending along one of said legs, another strip of fabric wound 25 upon the other of said arms beginning at its end and extending to the shoulder, thence around said body part and extending along the other of said legs, another strip of fabric folded over one shoulder of said frame 30 and extending along the leg opposite said shoulder, another strip of fabric folded over the other shoulder of said frame and extending along the leg opposite said shoulder, said two last named strips crossing one another, and means to bind said two last named strips about said legs and said body part.

Signed by me at Boston, Massachusetts, this 13th day of October, 1914.

MARJORIE T. GREGG.
